UNITED STATES PATENT OFFICE.

JAMES PETTIBONE, OF AVONDALE, OHIO.

DESIGN FOR A BALLOT-BOX.

SPECIFICATION forming part of Design No. 20,797, dated June 2, 1891.

Application filed May 9, 1890. Serial No. 351,189. Term of patent 14 years.

To all whom it may concern:

Be it known that I, JAMES PETTIBONE, a citizen of the United States, residing at Avondale, in the county of Coshocton, State of Ohio, have invented or produced a new and original Design for Ballot-Boxes, of which the following is a full, clear, and exact specification.

The object of this design is to provide a novel and distinguishing ballot-box; and the leading features thereof consist in a ballot-box formed to represent a human skull having a line of demarkation extending continuously round the crown portion and provided with an ornamental grip-handle extending rearwardly from the back of the skull.

The design is illustrated by the accompanying drawings, in which—

Figure 1 is a front elevation of the ballot-box, and Fig. 2 is a central vertical section of the same.

In the drawings, the letter A indicates the

front or face of the skull-shaped box; B, the crown; C, the lower jaw projected forward; D, the line of demarkation extending continuously round the crown portion and across the frontal bone, and E a projection at the back of the skull-shaped box. An ornamental grip-handle F projects rearwardly from the back of the skull at a point below the line of demarkation.

The design provides a peculiar, ornamental, and distinguishing ballot-box.

What I claim is—

The design for a ballot-box, substantially as shown and described.

In testimony whereof I have hereunto set my hand.

JAMES PETTIBONE.
